UNITED STATES PATENT OFFICE.

JOSEPH ROSARIO LAVIGUEUR, OF MONTREAL, CANADA.

COMBINED DOOR STOP AND CATCH.

SPECIFICATION forming part of Letters Patent No. 621,830, dated March 28, 1899.

Application filed June 4, 1898. Serial No. 682,546. (No model.)

To all whom it may concern:-

Be it known that I, JOSEPH ROSARIO LAVIGUEUR, a citizen of the Dominion of Canada, residing in the city and district of Montreal, Province of Quebec, Canada, have invented a certain new and useful Improvement in a Combined Door Stop and Catch, (for which I have obtained Canadian Patent, No. 59,579, dated April 9, 1898;) and I do hereby declare the following to be a full, clear, and exact description of the invention, such as will enable others skilled in the art to which it appertains to make and use the same.

My invention relates to improvements in door stops and catches.

The objects of my invention are to provide a device of this character which will, when the door is opened, stop its further movement and also hold it in its open position.

A further object is to provide a device which will be neat and attractive in appearance, durable in construction, and which can be manufactured at a moderate cost.

To these ends my invention consists in the improved construction and combination of parts hereinafter fully described, and particularly pointed out in the appended claim.

In the drawings, in which similar letters of reference indicate similar parts in all of the views, Figure 1 is a side elevation of my improved door stop and catch in position to hold the door open. Fig. 2 is a vertical longitudinal section of the same.

A designates my improved door stop and catch, composed of the plate *a*, which is adapted to be secured to the wall or washboard at a suitable point, and the pivotally-mounted member *a'*. The plate *a* is provided with two forwardly-extending lugs *a*², each lug being provided with an opening for the passage of a pivot *a*⁴, the ends of which extend outwardly from the outer faces of the lugs *a*².

The member *a'* is formed substantially as shown in the drawings, in which is shown a shell *a*⁵, having its sides extending downward and provided with openings *a*⁶ to receive the ends of the pivot *a*⁴. The front end of the member *a'* is provided with a suitable rubber tip *a*⁷, against which the door is adapted to abut.

A spring *a*⁸ is coiled about the pivot *a*⁴ be-

tween the lugs *a*², one end of which rests against the front face of the plate *a*, the other end resting against the under face of the member *a'*, as shown in Fig. 2. By this construction the member *a'* is held normally in a horizontal position, but by reason of its being pivotally mounted capable of being moved downward. The front end of the member *a'* is provided with an upwardly-extending lug *a*⁹, having its front face inclined, as at *a*¹⁰, the rear face being vertical, as at *a*¹¹.

B designates a catch secured to the door and having its rear end extending downward to form a lug *b*. The rear face of said lug is inclined or rounded, as at *b*', and the front face is vertical, as at *b*².

The operation of the device will be apparent. The door is pushed open until the face *b*' of the catch abuts against the inclined face *a*¹⁰ of the member *a'*. Continued pressure on the door causes the member *a'* to be pressed downward until the lug *a*⁹ has passed beyond the face *b*² of the catch, when the spring *a*⁸ will cause the member *a'* to be raised, which engages the lug with the catch. When it is desired to release the door, the member *a'* is pressed downward, releasing the engagement of the lug with the catch, when the door can be closed, the member *a'* resuming its normal position.

The advantages of this construction are many, among which may be included the non-liability of breaking, especially in the case of children playing in its vicinity.

It is obvious that an exceedingly strong and durably-constructed device is formed, which is neat and attractive in appearance and which can be manufactured at a moderate cost.

Having thus described my invention, what I claim as new is—

A combined door stop and catch, comprising a base-plate having forwardly-extending lugs; a pivot mounted in said lugs, said pivot having its ends extending beyond said lugs; a member, having a top and integral depending side flanges mounted pivotally on said pivot, the mounting being at the ends of said pivot; a spring mounted on said pivot between said lugs, said spring having one end contacting with said base-plate and having its opposite end engaging the under side of

said top whereby said member will be normally held in a horizontal position, said lugs and spring being in a position beneath and within said member, whereby accidental contact will be prevented; a lug formed at the front end of said member and extending outwardly therefrom, said lug having an inclined front face and a vertical rear face; a tip of resilient material connected to the front 5 end of said member; and a catch having a

depending lug adapted to ride over and engage the vertical face of the lug on said member, substantially as described.

In witness whereof I have hereunto set my hand in the presence of two witnesses.

JOSEPH ROSARIO LAVIGUEUR.
